Attorney

UNITED STATES PATENT OFFICE.

JOHN H. HYDE, OF TACOMA, WASHINGTON.

SHIP-BRAKE.

1,205,638.

Specification of Letters Patent. Patented Nov. 21, 1916.

Application filed April 8, 1915. Serial No. 19,980.

To all whom it may concern:

Be it known that I, JOHN H. HYDE, a citizen of the United States, residing at Tacoma, in the county of Pierce and State of Washington, have invented new and useful Improvements in Ship-Brakes, of which the following is a specification.

My invention relates to an improvement in ship brakes and is particularly designed 10 as an improvement over my prior Patent No. 1,087,660.

The principal object of my invention is to provide an arrangement in which strain of the brakes is not carried by the skin of the 15 ship but is transmitted directly to the stem.

A second object of my invention is to re-arrange the position of the braking members so as to take advantage of the stream line of 20 the water in the braking operation.

20 A third object of my invention is to provide improved means of arranging the cables for operating the braking members.

25 A fourth object of my invention is to provide improved mechanism for operating the braking members.

A final object of my invention resides in the particular arrangement and combination of parts hereinafter described.

In the accompanying drawings, Figure 1 30 is an elevational view of a ship having my invention applied thereto, parts being broken away for purposes of illustration. Fig. 2 is a top plan view of the ship shown in Fig. 1, the brakes being shown open in Fig. 2 and closed in Fig. 1. Fig. 3 is a detail view of the brake closing apparatus in plan, parts being broken away. Fig. 4 is a side view of the apparatus shown in Fig. 3. Fig. 5 is a detail view showing the arrangement 35 of the brake members along the side of the ship together with the cable arrangement and the air cylinder for opening the brake members.

Throughout the separate views the same 40 part is designated by the same reference character.

Referring more particularly to the drawings: 1 is the hull of a ship fitted with a plurality of pairs of brakes 2 and 3 arranged symmetrically on each side of the ship, there being five pairs shown on each side of the vessel. It will be seen, moreover, that the pairs of brakes are arranged in two groups, one group being near the bow and the other near the center of the ship. The 45 brakes in each pair are arranged overlap-

ping from rear to front, but with the rear brake placed considerably higher than the front one. Both the grouping arrangement and the arrangement of the individual 60 brakes in each pair is designed to take advantage of the stream line in the water and my experiments have shown that the arrangements just mentioned are most effective for this purpose.

In order to prevent undue strain on the skin of the ship when the brakes are thrown out to catch the water, I provide a series of girders or stringers such as 4 which run inside the skin and through which the hinges 70 of the brake members are connected as indicated at 5 in Fig. 5. These stringers run forward to the stem 6 where they are fastened and so relieve the ship skin of the strain. Moreover, the forward member 2 75 of each pair of brakes is provided with means whereby it may be thrust out from the side of the ship so as to catch the water. Such means comprise an air cylinder 7 having a piston rod 8 which extends through a 80 stuffing box 9 in the skin of the ship so that the rod can press against the inner face of the brake member 2. By such means any pair of the brakes or all of them may be thrust out when desired.

The brakes are drawn in by cables such as 10 which lead from the deck such as 11 down to a point opposite the brakes on the inside of the ship, the cables being run through pipe such as 12, the lower ends of which 90 make a water-tight fit with the inside of the skin of the ship as indicated at 13 so that the point where the rope passes through the skin does not need to be stuffed. The rope or cable is fixed to each of the respective brakes 95 as indicated at 14 and extend around a pulley such as 15 immediately within the skin of the ship, the pipe being enlarged at this point into an elbow 16 for the purpose of accommodating the pulley. One or more 100 pulleys such as 17 may be provided on the deck in order to properly guide the rope or cables. Above the deck 11 the cables are led to suitable means whereby they may be hauled in and held so as to keep the brakes 105 securely closed when not in use. Such means are illustrated in Figs. 3 and 4. I may also use guide rollers 50 outside the ship's skin.

Referring more particularly to Figs. 3 and 4, 18 indicates the steam cylinder of a 110 machine having a hand-operated valve 19 by which the steam may be admitted to either

side of the piston 20, the valve being operated either directly from the crank 21 or else by means of a handle 22 and a link 23 which may be hooked over the handle 24 on the crank 21. At the opposite end of the engine cylinder 18 is an air cylinder 24 having a piston 25 therein, the pistons 20 and 25 being directly connected by a rod 26 having a rack 27 incorporated as part thereof. 5 Meshing with the rack 27 is a pinion 28 which is keyed to a shaft 29. Keyed to the shaft 29 is a drum 30 having ratchet teeth 31 thereon, there being a hook-like pawl 32 pivoted to the frame 33 which may be 10 thrown over to coöperate with the teeth 31 so as to prevent the movement of the drum 30 in the clockwise direction when so desired. Loosely mounted on the shaft 29 is a second drum 34 having two sets of ratchet teeth 31' thereon and two pawls 32' whereby the drum 34 may be held against clockwise rotation as viewed in Fig. 4. Now the adjoining edges of the drums 30 and 34 are 15 toothed as indicated at 35 and I provide a spring 36 which tends to force the two drums apart so that the teeth will not engage. At the end of the shaft 29 opposite the pinion 28 I provide a casing 37 having a piston 38 therein and a rod 39 which runs 20 through the hollow end of the shaft 29 to a point of contact with a cross-piece 40 which works in a slot 41 in the shaft 29 and which contacts with a plate 42 so that when fluid is admitted into the casing 37 it presses the 25 piston 38, the rod 39, cross-piece 40, plate 41 and piston 34 against the pressure of the spring 36 so that the teeth 35 engage and the two drums are locked together.

Now the cables such as 10 are led to the 30 drums 30 and 34 in such a manner that the brake members 2 and 3 are drawn inwardly when the pistons 20 and 25 move from right to left when viewed as in Fig. 4. The rod 26 is sufficiently loose when it passes through the head of the air cylinder at 43 so that 35 there is no compression of air on the left hand side of piston 25 during this movement. When now it is desired to use the brakes the air cylinders 7 are operated to 40 push the point of the brakes beyond the recess 44 in which they are placed, this recess being provided in order to avoid any dragging effect by the brakes when they are closed and also to effectually prevent the 45 water from getting under the edges of brake and tending to open it when not desired. Of course, the pawls 32 and 32' are in engagement with their corresponding ratchets when the brakes are closed and these must 50 be first thrown off before the cylinders 7 are operated. As soon, however, as the cylinders 7 push the brakes out far enough to

catch the water there will immediately be a high pressure against the brakes tending to open them. This forces the piston 25 to 65 the right compressing the air in front of the pistons and thus preventing shock due to the sudden opening of the brakes as well as storing power for use on the closing stroke of the engine.

Assuming that it is desired only to use one of the pairs of brakes to assist in steering in an emergency, the drum 34 is allowed to remain out of engagement with the drum 30 and the pair of brakes operated by the 75 drum 30 is alone allowed to swing off, the drums 34 and the four pairs of brakes connected thereto being held by the pawls 32'.

Having thus described my invention, I 80 claim:—

1. The combination with a ship of at least one pair of brakes therefor, the brakes of each pair being arranged to overlap from the rear to the front and the rear brake being at a higher level than the front brake. 85

2. The combination with a ship having a stem of girders fixed to said stem and extending rearwardly within the skin of the ship and a brake hinged to the exterior of the ship, said brake being so connected to the 90 ship that the stress coming on the hinges is taken by said girders.

3. The combination with a ship of a plurality of brakes therefor, cables attached to said brakes, and means for hauling in said 95 cables comprising a steam cylinder having a piston therein, and means connected with said piston arranged to oppose the movement of the same on the off-stroke of the brakes and to assist the same on the inward 100 stroke of the brakes.

4. The combination with a ship of a plurality of brakes therefor, cables attached to said brakes, and means for hauling in said 105 cables comprising a steam cylinder having a piston therein, an air cylinder, and a piston in said air cylinder connected to said steam piston, said means being so arranged that air is compressed on the outstroke of the brakes whereby the air piston assists the 110 steam piston in drawing in the brakes.

5. The combination with a ship of a plurality of brakes therefor, cables attached to said brakes, coaxial drums to each of which a portion of said cables are connected, the 115 adjacent edges of said drums having interfitting teeth, means for holding the teeth of said drums out of mesh, means for throwing the teeth of the drums into mesh, and means for positively operating one of 120 said drums.

In testimony whereof I affix my signature.

JOHN H. HYDE.
